CLAIM

The ornamental design for a walking assistance attachment for snow ski, as shown and described.

DESCRIPTION

FIG. 1 is a perspective view of a walking assistance attachment for snow ski boots, showing my new design;
 FIG. 2 is a bottom plan view thereof;
 FIG. 3 is a top plan view thereof;
 FIG. 4 is a side elevational view thereof, the opposite side being identical; and,
 FIG. 5 is an end elevational view thereof, the opposite end being identical.

FIG. 2

FIG. 3

FIG. 4

FIG. 5
